UNITED STATES PATENT OFFICE.

CHARLES W. GOODING, JR., OF WILMINGTON, DELAWARE.

INTERNAL-COMBUSTION ENGINE.

1,330,629.

Specification of Letters Patent. Patented Feb. 10, 1920.

Application filed February 1, 1919. Serial No. 274,431.

To all whom it may concern:

Be it known that I, CHARLES W. GOODING, Jr., a citizen of the United States, residing at Wilmington, county of New Castle, and 5 State of Delaware, have invented a new and useful Improvement in Internal-Combustion Engines, of which the following is a full, clear, and exact description, reference being had to the accompanying drawings, which

10 form a part of this specification.

My invention relates to rotary internal combustion engines and particularly to those applicable to automobile, motor boat and aeroplane uses, when very high speed is desired combined with steadiness of running.

One type of such an engine is set forth in a patent granted to me December 7, 1915, No. 1,162,142, wherein pistons or vanes rotatable in a piston chamber at differential 20 and variable speeds on a common axis are connected by gearing with a driven member, such as a fly-wheel; said gearing comprising gear wheels, pinions, crank arms and links, the shafts of the pinions and crank arms 25 turning in bearings in a standard and being out of line with, but parallel with, the axes of the vanes and fly-wheel.

My invention comprises certain features of this patented engine but differs therefrom 30 in important, if not essential, particulars. In explosive engines of the rotary type it is the universal experience that gearing of any kind is highly objectionable, as it is difficult or impossible to so construct and arrange the gearing as to enable it to withstand the excessive shocks to which it is subjected by the sudden impulses imparted to the mechanism by the explosive character of the motive power. Moreover, it is more 40 or less objectionable to support any part of the intermediate mechanism in independent bearings, especially where they are out of line with the common axis of the piston chamber and the driven member. Most rotary internal combustion engines are open to objections of a similar character.

It is the object of my invention to substitute for the gearing of my said patent an entirely different mechanism so constructed 50 and arranged as to be adapted to resist all the shocks and strains to which it would necessarily be subjected. In its preferable embodiment such mechanism comprises a cam whose coöperation with turnable elements of the power transmitting mechanism

determines the differential movements of the two pistons or sets of pistons. The invention is capable of various specific embodiments but it will suffice to illustrate and describe one specific embodiment which, as 60 compared with others, presents the advantages of maximum simplicity of construction and smoothness of operation.

In the drawings:

Figure 1 is an elevational view partly in 65 section.

Figs. 2 and 3 are sections on the line 2—3 of Fig. 1, showing the power transmitting mechanism in different positions.

Figs. 4, 5, 6 and 7 are diagrams showing 70 the relative angular positions of the vanes at successive steps in the cycle.

The cylinder *a* is mounted on the base plate *b*, and contains the two diametral pistons consisting of vanes *c*, *c'*, *d*, *d'*. Vanes *c*, *c'* are connected to the enlarged portion *e'* of a shaft or sleeve *e*, mounted in bearings in the cylinder and its head *f*. Vanes *d*, *d'* are connected to a shaft or sleeve *g*, on sleeve *e*, whose diameter is the same as the enlarged 80 portion *e'* of sleeve *e*. Both sleeves turn on a shaft *h*. The cylinder is provided with an inlet port *i* and an exhaust port *j* and with a single spark plug *k*. A fan may be applied in the usual manner and the whole incased 85 in a draft hood, if desired, but such features are no part of the present invention and their illustration is unnecessary.

Secured to one of the shaft bearings *n* carried by the cylinder *a* is a fixed cam *o*, 90 which, in the specific embodiment shown, is of approximate elliptical or oval shape but provided with shallow concavities along parts of its circumference subtending the shorter radii of the ellipse or oval. Sleeve *g* 95 extends beyond cam *o* and carries a cross-head *p*. Sleeve *e* extends beyond the end of sleeve *g* and cross-head *p* and carries a cross-head *q*. On opposite ends of cross-head *p* are pivotally mounted links *r*, *r*. 100 On opposite ends of cross-head *q* are pivotally mounted links *s*, *s*. The adjacent ends of links *s* and *r* are turnable on pins *t*. These links *r*, *r*, *s*, *s*, thus form a frame shaped like a parallelogram or rhombus the form of 105 which deviates from a square to the extent that the cross-heads *p* and *q* deviate from a perpendicular relation. Turnable on the four pins *t* are rollers *u* which engage the operative face of the cam *o*. Also turnable 110

on two diametrically opposite pins *t* are blocks *v* slideable in guides *w* on the driven member or fly wheel *x* fixed to the shaft *e*.

It is obvious that with the fly wheel traveling at a substantially constant angular speed a similar constant angular speed of rotation about the common axis of the engine and fly wheel will be imparted to the blocks *v*. These blocks, however, partake of the movement of rollers *u*, which are forced out of a true circular path by the cam *o*, blocks *v* accommodating themselves to this radial displacement by sliding on the guide *w*. The shape of the cam is such that two diametrically opposite rollers *u*, *u*, are moving away from the axis while the other two rollers are moving toward the axis, and vice versa. The shape of the frame *r*, *r*, *s*, *s*, is thus constantly changing from a right angled rhombus or square to an oblique angled rhombus which necessarily imparts a variable angular speed of rotation to the two cross-heads *p* and *q* and the two sleeves *e* and *g* and therefore to the two pistons *d*, *d*' and *c*, *c*'. In other words, these two pistons, or two pairs of vanes, are so connected together, by mechanism between them and the driven member, that first one piston turns rapidly while the other turns slowly and then their relative speeds are reversed.

Having thus described the mechanism for impelling the pistons with variable and differential speeds, the cycle of operations may be readily understood. Assume the pistons to be in the position shown in Fig. 4. There is a compressed charge of explosive mixture between vanes *d* and *e*, which at this moment is ignited by firing plug *h* and vane *e* is impelled forward as shown in Fig. 5, discharging ahead of it the spent gases of the previous explosion through exhaust *j*. At the same time vane *c*' has drawn a fresh charge of explosive mixture through port *i* and compressed the preceding charge between itself and vane *d*. The parts are carried forward by expansion until in the position shown in Fig. 6, when firing of the last mentioned charge takes place. Vane *c*' is held practically stationary at this time, while vane *d* is impelled forward as shown in Fig. 7. In this movement the spent gases are exhausted, a charge of explosive mixture is compressed between vanes *d*' and *c*' and a fresh charge is drawn into the cylinder. Expansion carrying the parts forward to the firing position, it will be seen that the pistons will occupy the position of the pistons shown in Fig. 4, only transposed the one for the other. We have therefore been through a half revolution, the succeeding steps being exact repetitions. Each vane as it passes inlet port *i* draws a charge into the cylinder, at the same time compressing a charge ahead of it, the opposite vane meanwhile receiving the impelling force of

an explosion and at the same time expelling spent gases from a compartment ready for a new charge. Each piston is made alternately to do the work, while the other piston is held practically stationary.

Besides reducing friction to a minimum and providing mechanism which can easily absorb the shocks and strains transmitted by the explosive impulses of the motive power, it is obvious that the parts can be arranged and the cam shaped to impart to the rotating vanes any desired differential and variable speeds. Moreover, the provision of independently supported bearings and the transmission of power through mechanism turning on a plurality of non-coincident axes are avoided, thereby eliminating all influences tending to twist the parts out of the exact alinement which it is desirable to maintain.

The moving parts in the mechanism are similar, symmetrical and so balanced that the engine may be run with equal facility in either direction, merely necessitating the transposition of the inlet and exhaust ports.

Having now fully described my invention, what I claim and desire to protect by Letters Patent is—

1. In an internal combustion engine, the combination of a piston chamber, pistons rotatable therein, a driven element, and driving mechanism between both pistons and the driven element; said mechanism comprising a fixed cam, members so coacting with the cam and so connected with the driven element as to have imparted to them a combined constant angular speed of rotation about a common axis and a radial in and out movement, and mechanism connecting said members with the respective pistons adapted to impart to the pistons differential and variable speeds of rotation, said cam presenting a continuous working face shaped to insure a continuous coaction between the cam and said members.

2. In an internal combustion engine, the combination of a piston chamber, pistons rotatable therein, a driven element, and driving mechanism between both pistons and the driven element; said mechanism comprising a fixed cam, members so coacting with the cam and so connected with the driven element as to have imparted to them a combined constant angular speed of rotation about a common axis and a radial in and out movement, a common frame connected with said members, the parts of said frame being adapted to alter their relationship as the relative distances of said members from said common axis vary, shafts to which the respective pistons are secured and means connecting said shafts with the frame and adapted to impart to said shafts differential and variable speeds of rotation due to the alteration in relationship of the

parts of the frame, said cam being of an approximately oval contour but provided, on opposed sides, nearest its axes of rotation, with shallow concavities affording working faces merging into those parts of the cam more distant from its axis, thus affording a continuous working face with which all said members continuously and simultaneously coat.

In testimony of which invention, I have 10 hereunto set my hand, at Philadelphia, Pa., on this 22nd day of January, 1919.

CHARLES W. GOODING, JR.
